UNITED STATES PATENT OFFICE.

WILLIAM E. FOBES, OF GOSHEN, INDIANA.

MOLD.

987,225.

Specification of Letters Patent. Patented Mar. 21, 1911.

Application filed April 2, 1909. Serial No. 487,570.

To all whom it may concern:

Be it known that I, WILLIAM E. FOBES, a citizen of the United States, residing at Goshen, Indiana, have invented certain new 5 and useful Improvements in Molds, of which the following is a specification.

This invention relates to improvements in molds.

The main objects of this invention are: 10 First, to provide an improved face plate or pallet for molds, the body of which is formed of concrete, which is comparatively light in weight, and, at the same time, very strong and is not likely to be broken in use, 15 also one which is very durable. Second, to provide an improved face plate or mold which will impart to the article molded a natural cut stone appearance. Third, to provide an improved mold which can be 20 readily set up and knocked down, and is particularly adapted for my improved face plate.

Further objects, and objects relating to structural details, will definitely appear 25 from the detailed description to follow.

I accomplish the objects of my invention by the devices and means described in the following specification.

The invention is clearly defined and 30 pointed out in the claims.

A structure embodying the features of my invention is clearly illustrated in the accompanying drawing, forming a part of this specification, in which:

35 Figure 1 is a plan view of a mold embodying the features of my invention. Fig. 2 is a detail vertical section thereof. Fig. 3 is a detail perspective of one of my improved face plates or pallets. Fig. 4 is an enlarged 40 detail transverse section thereof taken on a line corresponding to line 4—4 of Fig. 3. Fig. 5 is an enlarged detail view showing the inside of the frame of my improved face plate or pallet. Fig. 6 is an enlarged detail 45 view of a modified structure, the flange at the edge of the frame being absent. Fig. 7 is a perspective view of my improved face plate adapted for use in the manufacture of fractional blocks, as they are commonly 50 termed. Fig. 8 is a detail section taken on a line corresponding to line 8—8 of Fig. 7.

In the drawings, similar reference characters refer to similar parts throughout the several views, and the sectional views are 55 taken looking in the direction of the little arrows at the ends of the section lines.

Referring to the drawing, the mold shown is particularly adapted for the manufacturing of hollow column blocks, and for this purpose I use one of my improved face 60 plates for each side of the mold. The face plate 1 consists of the metal frame 2, preferably formed of sheet metal having inturned flanges 3 at each edge. The body portion 4 is formed of concrete, and is preferably 65 cast within the frame 3. The outer side of the face plate is preferably a plain, flat surface, and flush with the outer edge of the frame, while the inner side contains a suitable pattern which is suitably formed to produce the desired conformation of the blocks. 70 The plate may be turned around when a flat faced block is desired. Thus the plate is adapted for forming two styles of blocks.

A binding strip 5 is preferably provided 75 to assist in securing the body within the frame. This is preferably formed of reticulated metal, (the so-called expanded metal being shown,) the edges of the strip being secured by folding or clamping the edges 80 of the body thereon, as clearly appears from the drawing. This binding strip is preferably bowed out in cross-section, as illustrated, so that it is effectively embedded in the body 4. It would, however, assist in 85 retaining or binding the body within the frame if it was laid flat on the frame.

The mold illustrated in Figs. 1 and 2 consists of a bottom or base plate 6, and a rectangular face plate supporting frame 7. 90 This frame is supported in an elevated position above the base plate by the rests 8. The face plates are arranged on edge on the base within the frame, one pair of face plates resting against the frame and the other 95 being supported by means of the wedges 9. The face plates are preferably provided at their ends with projecting lugs 10 adapted to engage the adjacent face plates. These lugs hold the face plates in proper relation 100 to each other and the frame, and the full face of each plate is brought into position. The inturned flanges 3 of the frames form a smooth edge or border line for the block, which further enhances the appearance of 105 the block. This border, where desired, I sometimes form in the concrete body of the block. The core 11 is preferably a block of wood having a handle 12 for convenience in handling. When it is desired to knock 110 down the mold for releasing the block, the core of wood is removed and the wedges 8

removed. This releases the frame so that it can be lifted off and the face plates or side walls of the mold are all released.

In Figs. 7 and 8, the structure is shown having a channel cross-piece 13 thereon, the edge of the cross-piece being flush with the edges of the frame. The structure is thus adapted to receive a partition plate or the like.

10. The mold illustrated shows one means of supporting my improved face plates or pallets in use. They are, however, adapted for use in various relations with various forms of molds and either as face plates or 15 pallets,—that is, they may be used to dry the blocks on after they are molded.

My improved face plate is very economical to produce, comparatively light in weight, and is very durable and not likely to 20 be broken from ordinary usage, and its edges are so protected that they cannot be chipped off, thereby disfiguring the blocks molded therewith or rendering the face plate or pallet useless.

25. Having thus described my invention, what I claim as new and desire to secure by Letters Patent is:

1. A structure of the class described, comprising a band-like metal frame having inwardly-projecting flanges at its edges; a reticulated strip arranged and secured within said frame by clamping the said inturned flanges of said frame upon its edges, said binding strip being bowed inwardly; and a 30 body of concrete molded into said frame, the outer side of said body being flush with the outer edge of the frame and the inner side being suitably conformed.

2. A structure of the class described, comprising a metal frame having inwardly-projecting flanges at its edges; a reticulated strip arranged and secured within said frame by clamping the said inturned flanges of said frame upon its edges, said binding 45 strip being bowed inwardly; and a body of concrete molded into said frame.

3. A structure of the class described, comprising a band-like metal frame; a reticu-

lated strip arranged and secured within said frame by folding the edges of said frame 50 upon its edges, said binding strip being bowed inwardly; and a body of concrete molded into said frame, the outer side of said body being flush with the outer edge of the frame and the inner side being suitably 55 conformed.

4. A structure of the class described, comprising a metal frame; a reticulated binding strip arranged and secured within said frame by folding the edges of said frame 60 upon its edges, said binding strip being bowed inwardly; and a body of concrete molded into said frame.

5. A structure of the class described, comprising a sheet metal frame; reticulated 65 binding strips arranged within said frame parallel with the side and end pieces thereof, the edges of said frame being folded inwardly upon the edges of said binding strips, whereby they are retained in position in said 70 frame; and a body of concrete molded into said frame upon said binding strips.

6. In a structure of the class described, the combination with a base of a frame; rests on said base for said frame; side walls 75 arranged in said frame, said side walls having lugs at their ends adapted to engage the ends of the adjacent walls; oppositely disposed wedges for supporting one pair of 80 said side walls, and a removable core plug. 80

7. In a structure of the class described, the combination with a base of a frame; rests on said base for said frame; side walls arranged in said frame, said side walls having lugs at their ends adapted to engage the 85 ends of the adjacent walls; and oppositely disposed wedges for supporting one pair of said side walls.

In witness whereof, I have hereunto set my hand and seal in the presence of two witnesses. 90

WILLIAM E. FOBES. [L.S.]
